ATTORNEY

UNITED STATES PATENT OFFICE.

HUGO A. BUCCINI, OF PHILADELPHIA, PENNSYLVANIA, ASSIGNOR TO VICTORY LAMP COMPANY, OF PHILADELPHIA, PENNSYLVANIA.

DESIGN FOR AN ELECTRIC-LIGHTING WALL FIXTURE.

Application filed December 19, 1927. Serial No. 24,538. Term of patent 3½ years.

To all whom it may concern:

Be it known that I, HUGO A. BUCCINI, a citizen of the United States, and a resident of Philadelphia, county of Philadelphia, State of Pennsylvania, have invented a new, original and ornamental Design for an Electric-Lighting Wall Fixture (Case 180), of which the following is a specification, reference being had to the accompanying drawing, forming a part thereof.

In the drawings accompanying this application:—

Figure 1 is a front elevational view of the electric lighting wall fixture; and

Figure 2 is a top plan view showing the general contour of the fixture.

I claim:

The ornamental design for an electric lighting wall fixture as shown.

HUGO A. BUCCINI.
